Inventor,
A. H. Knapp,
By his Atty,
J. S. Brown.

United States Patent Office.

A. H. KNAPP, OF NEWTON CENTRE, MASSACHUSETTS.

Letters Patent No. 60,908, dated January 1, 1867.

IMPROVED CURTAIN FIXTURE.

The Schedule referred to in these Letters Patent and making part of the same.

TO ALL WHOM IT MAY CONCERN:

Be it known that I, A. H. KNAPP, of Newton Centre, in the county of Middlesex, and State of Massachusetts, have invented an Improved Window-Shade Fixture; and I do hereby declare that the following is a full and exact description, reference being had to the accompanying drawings, making part of this specification—

Figure 1 being a front view of the fixture as applied with a window-shade to a window.

Figure 2 a side view of the shade roller or stick.

Figure 3 a transverse section of the roller.

Figure 4 a side view of one of the journal bearings of the roller.

Figure 5 a cross-section of the balance spring and parts connected directly therewith.

Like letters designate corresponding parts in all of the figures.

To balance the shade, I make use of a simple coiled spring, B, arranged in one of the supporting brackets, as A, of the fixture, working perfectly when the motion of this spring is geared up to a sufficient increase to enable the spring to be reduced in strength and the roller to have enough extent of movement to correspond with the weight of the shade and the distance it has to move to shade the window. In order to effect this gearing up of the motion from the spring, a single cog-wheel, E, on the shaft C of the spring, and of about the size shown, and gearing into a pinion, F, also of about the size indicated, will be suitable for ordinary use. The shaft I of the pinion F is provided with a square or equivalent form of coupling projection, d, to fit into a socket of the same form and size in the end of one of the journal bearings H of the roller, as shown at f, figs. 2, 3, and 4. The other journal of the roller rests in a simple bracket, K, as seen in fig. 1. Thus arranged, the end of the roller resting in the bracket K is readily lifted out therefrom at any time, when it can at once be uncoupled from the geared shaft I of the bracket A. In connection with this construction and arrangement of the spring and its connecting parts, as described, there is also to be added a projecting knob or milled head, D, on the shaft C of the spring. The use of this knob is to wind up the spring or to hold the spring from unwinding when the shade roller is disconnected from the geared shaft I. And when the shade is found to be either too heavy or too light for the spring, as adjusted at any time, the roller is to be disconnected from the shaft I and the spring wound up a little more or unwound a little by the knob D, to adjust the strength exactly as desired. The spring is so adjusted that, when left to itself, the shade will neither be wound up nor unwind at any height; but by lifting a little at the lower end thereof it will immediately ascend. The spring shaft C may have the usual ratchet-wheel, b, and pawl, c, to enable it to be wound up at any time, and adjusted to greater strength without disconnecting the shade roller. But this ratchet-wheel and pawl may be dispensed with. The bracket A may have a cover, a, to conceal the movement inside, and may have any desired form and finish for ornamental appearance. The shade L is attached to the roller E by a groove in the roller, in which the upper end of the shade is held by a wedge strip, g, as shown. I also make a square or angular hole or recess, G, entirely through the centre of the roller, from end to end, for the reception of the shanks of journal bearings H, H, as represented. This recess is made in connection with the wedge groove in the roller. Otherwise it would be difficult and costly to make. The object of this is to enable the roller to be cut to any length and yet have the journal bearings applicable to the ends anywhere, the shanks thereof fitting the same at all points in its length. This fixture works quite perfectly, is not liable to get out of order, and is comparatively very cheap for a balance fixture.

What I claim as my invention, and desire to secure by Letters Patent, is—

The combination of the projecting knob or milled head D with the coiled spring B, cog-wheel and pinion E and F, and roller coupling d, substantially as and for the purpose herein specified.

I also claim the square, angular, or equivalent form of recess G, through the centre of the roller, formed in connection with the wedge groove therein, for the purpose set forth,

A. H. KNAPP.
